US0D1032259S

(12) **United States Design Patent** (10) **Patent No.:** **US D1,032,259 S**
(45) **Date of Patent:** ** *Jun. 25, 2024

(54) **DISPLAY STAND**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/725,293**

(22) Filed: **Feb. 24, 2020**

Related U.S. Application Data

(63) Continuation of application No. 29/701,099, filed on Aug. 8, 2019, now Pat. No. Des. 876,132, which is a continuation of application No. 29/677,279, filed on

Jan. 18, 2019, now Pat. No. Des. 856,046, which is a continuation of application No. 29/604,053, filed on May 15, 2017, now Pat. No. Des. 838,524, which is a continuation of application No. 29/561,220, filed on Apr. 14, 2016, now Pat. No. Des. 789,123, which is a continuation of application No. 29/541,528, filed on Oct. 5, 2015, now Pat. No. Des. 753,942, which is a continuation of application No. 29/500,897, filed on Aug. 29, 2014, now Pat. No. Des. 740,060.

(57) **CLAIM**

The ornamental design for a display stand, as shown and described.

DESCRIPTION

FIG. 1 is a top front perspective view of a display stand showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a right side view thereof showing the display stand in an environment in which it may be used.

The broken lines in the figures show portions of the display stand or environment that form no part of the claimed design.

1 Claim, 6 Drawing Sheets

FIG. 1

FIG. 2

FIG. 3

FIG. 4

FIG. 5

FIG. 6**FIG. 7**

FIG. 8
